WILLIAM W. HOWELL, OF PHILADELPHIA, PENNSYLVANIA, ASSIGNOR TO
HIMSELF AND M. MARSHALL, OF SAME PLACE.

Letters Patent No. 63,637, dated April 9, 1867.

IMPROVEMENT IN ROLLING-MILLS.

The Schedule referred to in these Letters Patent and making part of the same.

TO ALL WHOM IT MAY CONCERN:

Be it known that I, WILLIAM W. HOWELL, of Philadelphia, Pennsylvania, have invented certain Improvements in Rolling-Mills; and I do hereby declare the following to be a full, clear, and exact description of the same, reference being had to the accompanying drawing, and to the letters of reference marked thereon.

My invention relates to that class of mills in which a shield is used for turning the end of a bar passed between the rollers, back to the side from which it was introduced; and my invention consists of certain springs described hereafter, for aiding the operator in introducing the bar to the desired groove, and guiding the bar as it is turned up, and directing it in its proper course between the rolls.

In order to enable others skilled in the art to make and use my invention, I will now proceed to describe its construction and operation, reference being had to the accompanying drawing, in which—

Figure 1 represents a vertical section of sufficient of a rolling-mill to illustrate my improvement; and

Figure 2 a sectional plan.

A and B are the upper and lower rolls, in which are grooves and projections adapted in the present instance for the manufacture of ordinary bar-iron, the journals *b b* of the rolls turning in the direction of the arrows in standards of the usual construction, and these standards being secured to a suitable base-plate, the upper surface of which is represented by the line D. To the base-plate are secured as many plates or shields E E as there are spaces between the rolls, through which spaces the bar has to be passed, there being in the present instance one shield beneath each groove in the lower roll, although a single shield for the whole of the grooves may be used. Immediately above each shield, and to the base-plate D, is secured a spring, *a*, there being one spring for each of the grooves in the lower roll, the outer end of the spring being so elevated as to enter a short distance into the groove. Each shield is curved upward at the rear, as represented in fig. 1. The operator takes his stand in front of the machine, and pushes the end of the heated bar *x* in the direction of the arrow 2, beneath the lower roll B, and above the spring *a*, into one of the grooves with which the spring coincides. By the movement of the lower roll in the direction of the arrow, and guided by the curved portion of the shield, the bar is bent and carried upwards, and passes between the rolls within the groove into which it was first introduced, the bar finally taking its place on the floor in front of the rolls, where it is again seized by the operator, who introduces it to another groove prior to its further reduction by a second passage into another groove between the rolls, and this operation is continued until the bar is reduced to the desired size. The springs *a* perform the important duties of aiding the operator in guiding the bar into the groove, and of maintaining it there, as the bar is turned upwards and passed between the rolls as described.

I claim as my invention, and desire to secure by Letters Patent—

The combination of the recessed roller B, roller A, shields E, and springs *a*, the whole being arranged and operating as described.

In testimony whereof I have signed my name to this specification in the presence of two subscribing witnesses.

WILLIAM W. HOWELL.
